Filed Feb. 22, 1972, Ser. No. 228,448

Term of patent 7 years

Int. Cl. D6—04

U.S. Cl. D69—1

FIG. 1

FIG. 4

FIG. 2

FIG. 3

FIG. 1 is a top plan view of a self-deposit receptacle for banks showing my new design;

FIG. 2 is a front elevational view thereof;

FIG. 3 is a side elevational view thereof; and

FIG. 4 is a bottom plan view thereof.

The rear elevational view appears the same as the front elevational view and both side elevational views are the same.

I claim:

The ornamental design for a self-deposit receptacle for banks, substantially as shown and described.
